Primary Examiner — Susan Bennett Hattan*Assistant Examiner* — Marie Fast Horse(74) *Attorney, Agent, or Firm* — Li & Cai Intellectual Property (USA) Office(57) **CLAIM**

The ornamental design for a “wireless access point,” as shown and described.

DESCRIPTION

FIG. 1 is a perspective view of a wireless access point showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view viewed from another visual angle thereof.

The broken lines in the drawings depict portions of the wireless access point that no part of the claimed design.

1 Claim, 6 Drawing Sheets(56)
